REFRIGERATING SYSTEM

Wilfred Fourness, Oakland, Calif., assignor, by
mesne assignments, to Fourness Development
Corporation, Ltd.

Application April 4, 1932, Serial No. 602,968

10 Claims. (Cl. 62—115)

This invention relates to a refrigerating system, and especially to one employing a refrigerant circulating in a closed-circulatory path. Such systems in general are well known, and usually employ such mediums as sulfur dioxide or its equivalent.

The medium is placed in a liquid stage, and then permitted to evaporate or "expand" in a closed space, such as a coil or chamber. The process of evaporation into a gas or vapor form entails absorption of heat, producing the desired refrigerating effect at and adjacent the expansion coils. After evaporation, the gas is led to a compressor where it is compressed, and then it is passed to a condenser where it is recondensed. There it is allowed to pass as needed into the expansion space, as by the aid of an expansion or float valve or other means. In this way the cycle is repeated again and again.

In such well-known systems, it sometimes happens that the condenser exhibits a tendency to retain some of the condensed liquid, thereby causing a higher discharge pressure between the compressor and the condenser, than if the condenser were completely purged of the liquid. It is one of the objects of my invention to make it possible to purge the condenser completely, thereby ensuring favorable operating conditions for the condenser; and especially by providing an intermediate receiver to which the condenser discharges, and in which the pressure is lower than in the condenser. This lowering of pressure is preferably accomplished by the aid of a cooling means in or near this receiver, such as a water cooling coil, or a small expansion coil through which the refrigerant must pass.

It is also sometimes desirable to operate a number of compressors in parallel for a single refrigerating system. In such installations, two or more compressors are driven either by a common source of power or by independent sources, and the vaporized or gaseous refrigerant from the expansion coil is led to the intakes of all the compressors. Each compressor has its own condenser, and then the condensed refrigerant from all of the condensers is fed to a common control valve to the expansion space.

Under such circumstances, the division of the load between the compressors is apt to be very unequal. This may be due to slight differences between the respective intake pressures, or the respective discharge pressures, which may initiate a condition that progresses toward extremely heavy load conditions for some or one of the

units, and extremely light load conditions for other units.

It is another object of my invention to ensure substantially equal load division between the compressor units.

This I accomplish by using a common intermediate receiver into which all of the condensers discharge. This intermediate receiver is so arranged that it completely purges all of the condensers, as by cooling it in the manner hereinabove described.

My invention possesses many other advantages, and has other objects which may be made more easily apparent from a consideration of several embodiments of my invention. For this purpose I have shown a few forms in the drawing accompanying and forming part of the present specification. I shall now proceed to describe these forms in detail, which illustrate the general principles of my invention; but it is to be understood that this detailed description is not to be taken in a limiting sense, since the scope of my invention is best defined by the appended claims.

Referring to the drawing:

Figure 1 is a diagram of a system utilizing a single compressor, in which my invention is incorporated; and

Fig. 2 is a similar diagram of a system utilizing a number of compressors.

In Fig. 1 the closed cycle for the refrigerant includes an expansion or evaporation space 11, usually in the form of a coil of tubing. It is in this space that the liquid refrigerant absorbs heat. From the space 11 the refrigerant is led as by a conduit 12, to the inlet of a compressor 13. The discharge from this compressor connects to a condenser 14, where the compressed gas is condensed.

With my invention, there is provided a receiver 15 into which the condenser discharges, and which retains the liquid refrigerant until it is passed to the space 11. This intermediate receiver is maintained at a temperature less than that of condenser 14, as by artificial cooling, and in a manner that will be described shortly. In this way, there is an assurance that the pressure in receiver 15 is less than in the condenser 14, and therefore the condenser 14 will be completely purged of the condensed refrigerant.

The refrigerant then proceeds as by conduit or pipe 16, to a valve 17, such as an expansion valve, for automatically feeding the refrigerant to the space 11, intermittently as required. But

before the refrigerant reaches this space, it is caused to travel through a cooling coil 18 in or near receiver 15 for cooling it. To effect this result, a pipe 19 leads from valve 17 to coil 18, and from there, a pipe 20 conducts the refrigerant to the space 11. In coil 18, a slight evaporation is permitted to absorb heat from the refrigerant collected in receiver 15. This causes a slight temperature differential between the receiver 15 and the condenser 14, of the order of a few degrees. The refrigerant, after expanding in space 11, then repeats the cycle.

The mode of operation of the system is apparent from the foregoing. The condenser 14 is purged from all its refrigerant and compressor 13 can operate at its best efficiency.

The use of an intermediate receiver is especially beneficial where there are a plurality of compressors operating in parallel as in Fig. 2. Here the compressors 21, 22 have their inlets connected by way of the common pipe 23 to the outlet of expansion space 11. Each compressor however discharges to its own condenser 24 or 25; but both condensers discharge into the common intermediate receiver 15, as by the aid of the branched pipe 26. Thence the refrigerant proceeds as before through the valve 17, pipe 19, cooling coil 18 in receiver 15, and pipe 20 to space 11.

Due to the use of the common receiver 15, which is kept by cooling it, at a lower pressure than condensers 24, 25, these condensers are kept purged of refrigerant. Accordingly the division of the load between the compressors is stabilized, both inlet and outlet pressures being maintained substantially uniform for all of the compressors.

I claim:

1. In a refrigerating system utilizing a refrigerant that is cyclically liquefied, evaporated, and compressed by the aid of a compressor, the process which comprises condensing the refrigerant after it is compressed, passing the refrigerant after it is condensed, to a region at a temperature slightly below that of the space where the liquid is condensed, and retaining the refrigerant in that region until it is passed to an evaporating space.

2. In a refrigerating system utilizing a refrigerant that is cyclically liquefied, evaporated, and compressed by the aid of a compressor and a condenser into which the compressor discharges, the process which comprises passing the liquid refrigerant from the condenser into an intermediate receiver, and cooling said receiver so that there is a slight temperature differential between the receiver and the condenser by expansion of the refrigerant in its passage to the evaporation space.

3. In a refrigerating system utilizing a vaporizable refrigerant, a compressor, a condenser, an intermediate receiver to which the condenser discharges, and where the refrigerant is retained and means for maintaining said receiver at a slightly lower temperature than the condenser, comprising a cooling coil in the receiver.

4. In a refrigerating system utilizing a vaporizable refrigerant, a plurality of compressors

operating in parallel, and means ensuring against substantial load inequality between the compressors comprising condensers connected with the compressors, an intermediate receiver for drawing condensed refrigerant from each condenser, and means forming a common expansion space connected to the intermediate receiver.

5. In a refrigerating system utilizing a vaporizable refrigerant, a plurality of compressors operating in parallel, a condenser for each compressor, an intermediate receiver into which all of the condensers discharge, and where the liquid refrigerant is retained until it is passed to an evaporating space, and means for maintaining said receiver at a temperature below that in the condensers.

6. In a refrigerating system utilizing a vaporizable refrigerant, a plurality of compressors operating in parallel, a condenser for each compressor, an intermediate receiver into which all of the condensers discharge, and where the liquid refrigerant is retained until it is passed to a common evaporating space, and means for cooling said receiver to a temperature below that in the condensers.

7. In a refrigerating system utilizing a vaporizable refrigerant, a plurality of compressors operating in parallel, a condenser system connected to the compressors, means forming a common expansion space discharging to the compressors and an intermediate receiver into which the condenser system discharges, and where the refrigerant liquid is retained until it is passed to an evaporating space.

8. In a refrigerating system utilizing a vaporizable refrigerant, a plurality of compressors operating in parallel, a condenser system connected to the compressors, an intermediate receiver into which the condensers discharge, and where the liquid refrigerant is retained until it is passed to the evaporating space, and means for cooling said receiver below the temperature of the condenser system.

9. In a refrigerating system in which a vaporizable refrigerant is used, a compressor, a condenser, an intermediate receiver in which said refrigerant is retained, a conduit connecting the condenser and the intermediate receiver, and means forming a circuit from the intermediate receiver back to the intake of the compressor, said circuit including an expansion space and a path in series with said space and in heat exchange relation with the interior of the receiver for causing a slight temperature differential to exist between the interior of the receiver and the interior of the condenser.

10. In a refrigerating system in which a vaporizable refrigerant is used, a plurality of compressors, a condenser system into which the compressors discharge, an intermediate receiver into which the condenser system discharges, and means forming a circuit from the intermediate receiver to the intake of the compressors, said circuit including an expansion space and a path in series with said space and in heat exchange relation with the interior of the receiver to reduce the temperature of said interior.

WILFRED FOURNESS.
